UNITED STATES PATENT OFFICE.

EDWIN W. ABBE, OF NEW BRITAIN, CONNECTICUT.

SASH-CORD FASTENER.

SPECIFICATION forming part of Letters Patent No. 397,680, dated February 12, 1889.

Application filed December 31, 1888. Serial No. 294,985. (No model.)

To all whom it may concern:

Be it known that I, EDWIN W. ABBE, a citizen of the United States, residing at New Britain, in the county of Hartford and State 5 of Connecticut, have invented certain new and useful Improvements in Sash-Cord Fasteners, of which the following is a specification.

My invention relates to improvements in sash-cord fasteners of the class which are 10 designed to be fastened to a cord without tying a knot therein; and the objects of my invention are simplicity in construction and convenience and efficiency in use.

In the accompanying drawings, Figure 1 is 15 a plan view of my sash-cord fastener with a cord attached thereto. Fig. 2 is a front elevation of the same. Fig. 3 is a vertical section on line *xx* of Fig. 1, together with a portion of a sash; and Fig. 4 is a like sectional 20 view of my sash-cord fastener alone.

The general form of my fastener may be described as consisting of two circular plates, 5 5, connected by a semi-cylindrical shell or frame, 6, the same being adapted for use by 25 being slipped into a round hole in the sash A at the termination of the cord-receiving groove B in the edge of the sash.

A sash-cord fastener of this general form, in which the cord C is secured therein by a knot 30 or clasp on the end of the cord with said knot or clasp resting upon the inside of the shell, is old, and is hereby disclaimed.

I dispense with a knot or specially-formed clasp on the end of the cord. Between the 35 two end plates, 5 5, I form a cross-bar, 7, and integral with each of the end plates, 5 5, toward their lower edge, I form a tongue, 8. The top of the shell immediately opposite said tongues is left open for the passage of the 40 cord C. The cord is then passed through one of these openings, doubled over the lower edge of the cross-bar, passed up through the opening in the shell on the other end of the fastener, when the tongues 8 8 are bent or pressed 45 inward by striking them with a hammer or otherwise imparting a like pressure, so as to

bind the metal firmly upon the cord upon both sides of the cross-bar 7. The cord may then be cut off on one side substantially even with the outside of the shell, and the device 50 is ready to be applied to the sash A, as illustrated in Fig. 3. I prefer to thicken the tongues 8 somewhat at their upper ends, so that in their normal position they will project slightly beyond the outer faces of the end 55 plates, 5 5, while their inside is even with the inner face of said plate, as shown in Fig. 4, whereby their outer face, after the cord has been secured thereto by bending the tongues, will be even with the outer faces of the end 60 plates, as shown in Fig. 3.

While I prefer to form a tongue, 8, at each 65 end of the fastener for convenience of putting the cord in place and for gripping the cord firmly at two different points upon the respective sides of the cross-bar 7, an efficient fastener may be formed by the employment of only one such tongue for fastening that end of the cord which terminates at the fastener. 70

When fastened by either one or two tongues, the fastening is very secure and efficient on account of the cord being doubled over the cross-bar, so that it has an indirect pull on the fastener; and, furthermore, the fastener is 75 particularly adapted for use with hard cords, which are very inconvenient, if not impracticable, to firmly secure by tying a knot.

I claim as my invention—

The herein-described sash-cord fastener, 80 consisting of the end plates connected by a shell or frame, the cross-bar between said end plates for doubling the cord over, and a fastening-tongue formed integral with one or both of said end plates for impinging upon the cord, 85 substantially as described, and for the purpose specified.

EDWIN W. ABBE.
